UNITED STATES PATENT OFFICE

1,922,950

SPINNING APPARATUS

Thomas Harris, Providence, R. I.

Application November 17, 1932
Serial No. 642,998

12 Claims. (Cl. 19—130)

This invention relates to a spinning apparatus and is a continuation in part of my co-pending application Serial No. 527,498, filed April 3, 1931, it has for one of its objects the provision of a 5 construction for long draft spinning in a single unit.

Another object of the invention is to eliminate the handling of the work between different processes in providing a yarn suitable for weaving, 10 and other purposes.

A further object of the invention is the provision of a construction which will act upon a large sliver and control the selvages of the sliver in its passage thru different operations for reducing it to the size of yarn desired.

A still further object of the invention is the provision of a more even yarn by spinning the same from the sliver where its size and weight per unit of length are substantially even.

20 Another object of the invention is the provision of a construction which may be controlled for each yarn end so that but one end in the spinning operation will be stopped should the yarn break, without the necessity of stopping other 25 companion units for operating other slivers of yarns.

A still further object of the invention is the provision of a construction in which one of a plurality of nip rolls which engage the strand as it passes thru the apparatus will traverse one 30 with reference to the other as they revolve that the wear may be distributed over the surface of the rolls rather than occur in one particular part thereof.

35 With these and other objects in view, the invention consists of certain novel features of construction, as will be more fully described, and particularly pointed out in the appended claims.

In the accompanying drawings:

40 Fig. 1 is a sectional view of my apparatus illustrating different nip rolls as positioned in one position of their operation.

Fig. 2 is a plan view of one of the units which are slidably mounted in the frame and showing 45 portions of the frame in section.

Fig. 3 is a plan view of the slide plate which is slidably mounted on each of a plurality of decks.

50 Fig. 4 is a sectional view on the line 4—4 of Fig. 3.

Fig. 5 is a top plan view of the member which is rotatably mounted on the plate and of the construction shown in Figures 3 and 4.

55 Fig. 6 is a sectional view on line 6—6 of Fig. 5.

Fig. 7 is a sectional view on line 7—7 of Fig. 5.

Fig. 8 is a sectional view on line 8—8 of Fig. 5. Fig. 9 is a perspective view of the driving roll and the traversing roll showing the carriage in which the traversing roll is mounted and its link connection to a portion of the lever for operating 60 the same.

Fig. 10 is a sectional view showing the locking mechanism and taken on line 10—10 of Fig. 2.

Fig. 11 is a diagrammatic view of the driving mechanism for the different rotary members 65 which are mounted upon the plates of the apparatus.

Cotton sliver from the card is usually doubled or several ends placed together thru a drawing frame, then a slubbing process and two or three 70 intermediate roving processes before spinning. A twist is placed in the roving in order that it may be pulled from one place to another, and in order to eliminate several processes and spin the yarn directly from doubling where it is 75 more even, I place a false twist in the sliver between each pair of drawing rolls to control the edges of the sliver and prevent the fibers at the edges thereof from fraying; and in order that the yarn may not be too tightly falsely 80 twisted between the receiving and delivery rolls by which drawing will be retarded or prevented, I may place a false twist in the yarn in one direction between the first two pairs of drawing 85 rolls and in the opposite direction between the next pair of drawing rolls and so forth thru the machine, whereby I may take the sliver directly from the doubling operation and spin the same with a long draft, thereby eliminating 90 the slubbing and the intermediate roving processes and from which I may finally obtain an extremely long draft of yarn without fraying of the edges and a yarn of improved quality by reason of the fact that I spin the yarn directly 95 from the doubling process at which point it is more even in weight and size than at any other step in the operation; and the following is a detailed description of the present embodiment 100 of this invention illustrating the preferred means by which these advantageous results may be accomplished:—

With reference to the drawings, 10 designates the frame work of my construction, which consists of a plurality of decks which I designate as 11, 12, 13, 14, 15 and 16, which are supported by suitable standards 17, maintaining them in the desired spaced relation which may be adjustable if desired by some suitable means.

Upon each of these decks, except the upper one 110 11, there is mounted a slide plate which I will

designate 18, 19, 20, 21, 22 and 23. The upper plate 18 has a central opening and is provided with bearings 24 and 25 fixed thereon to rotatably support a fluted roll 26 therein, which roll 5 is driven by means of a worm 27 and worm gear 28, from a suitable source of power supported by the frame work of the machine. A companion roll with an axis parallel to the axis of the roll 26 is yieldingly pressed towards the roll 26 to 10 provide a nip on the yarn in a well known manner.

The plates 19, 20, 21 and 22 are formed differently than the plate 18 and are illustrated in a plan view, shown in Fig. 3, and in section in 15 Fig. 4. In each of these plates there is a central opening 29 with inwardly-extending gear teeth 30 provided around the edge thereof. The plate is provided with a finished surface 31 providing one part of the ball race and supporting balls 20 32 which in turn support a rotary member 33, which is shown in plan view in Fig. 5 and in section in Fig. 6. This rotary member is of dish shape and is provided with teeth 34 in a plane above the plate to mesh with a driving gear. 25 The drive for each rotary member differs in that each is rotated in the opposite direction from the next member. One form is shown in Fig. 2, there showing a driving gear 35 which in turn is driven by a train of gears 36, 37 and 38 connected to the drive shaft 39.

This rotary member carries a shaft 40 upon which a pinion gear 41 is mounted, which pinion gear is positioned to engage with the internally extending teeth 30 of the plate so as the rotary 35 member turns about its own axis the shaft 40 will be rotated.

Upon this shaft 40 a worm gear 42 is provided which drives the worm 43 which is fixed on the worm shaft 44 upon which roll 45 is mounted, 40 this shaft being suitably supported in bearings 46 and 47 fixed upon the rotary member 33. The pitch of the teeth on the worm 43 and gear 42 will vary to cause the desired direction of rotation of travel. The companion nip roll 48 is 45 suitably supported in a carriage 49 which may be slid over the surface of the rotary member supported by a boss 50, shown best in Fig. 6, and which carriage is forced towards the drive roll 45 by means of helical springs 51 abutting at one 50 end 52 in the rotary member and encircling a pin 53 rockably supported in the carriage 49, whereby they may cause pressure to be applied to the roll in different positions of its axial movement with respect to the roll 45.

55 This carriage is slideable along the rotatable member and beneath a plate 54 which is held by bolts 55 firmly against an abutment 56 so that the carriage is guided in its travel between this plate and the slide surface 50 on the rotatable member.

In order that oscillating movement may be imparted to the carriage 49 and its roll 48, I have provided a worm 57 on the end of the roll shaft 44 with which there meshes a worm gear 58 fixed 60 to a shaft 59 and rotatably supported in the rotary member 33. Below the gear 58, there is a spur gear 60 which meshes with an intermediate gear 61 fixed to a shaft 62 upon which there is also mounted a spur gear 63, which gears with gear 64 fixed upon another shaft 65 upon which 70 there is provided a heart-shaped cam 66. A lever 67 pivoted upon the shaft 59 has a bifurcated end 68 to engage the heart-shaped cam for oscillating about the pivot or shaft 59 in response to movement of the cam.

A link 69 connects the free end of the lever 67 with the carriage so that as the cam operates the roll 48 will be oscillated axially back and forth across the roll 45 so that its leather covered surface will not become worn by travel of the strands between it and the metal fluted roll 45 in any one place. A finger piece 70 is provided upon the carriage in order that the roll may be manually separated for taking out roll or other purposes.

Each of the plates 19, 20, 21 and 22 is slideable into place on its deck and each is similarly equipped and they are arranged so that their pairs of rolls are at substantially right angles one to the other. The revolving of the rolls about a center between them is had in opposite directions by adjacent decks so that they impart a false twist in the yarn. In Fig. 11, I have illustrated diagrammatically the rotary members A, B, C and D, comparable to the members 33 on the plates, 19, 20, 21 and 22 which are driven from a drive shaft 39. The upper rotary member A is shown as driven from the gear 72 thru an intermediate gear 73. The next rotary member B is shown as driven from gear 74 thru two intermediate gears 75 and 76, in order that a reverse rotation may be imparted thereto. The next rotary member C is rotated from gear 77 thru a single intermediate member 78, in order that it may have the same rotation as rotary member A, while rotary member D is driven directly from gear 79 on the drive shaft that it may have the same direction of rotation as the rotary member B. The worm and gear 42 and 43 will on members A and C have an opposite pitch from the similar worm and gear on members B and D. It will also be understood that the nip rolls are so geared as to rotate progressively faster that a draft may be had between them and the fibers pulled out to provide a yarn of the desired size.

The lower draft rolls on the plate 23 are similar in many respects to the mounting of the draft roll on the plate 18. Bearings 80 and 81 are provided in which the driven roll 82 is mounted which is driven from the drive shaft 71 thru suitable mitre gears 83 and 84. A companion roll back of this drive roll is suitably supported and given the usual traverse motion which need not here be described.

Each of the plates upon which the rotary members and rolls are mounted may be slid into or out of the decks by a simple withdrawing operation which may be had by reason of the handle 85 mounted upon each of these plates. Each 130 plate is held in position with its gears, the teeth of their rotary members 33 being in proper intermeshing relation by reason of the pin shown at 86 in Fig. 9, which is operated by a rotary shaft 87 having a handle 88.

By this construction a long draft may be provided in a single unit, the sliver being taken from the large doubling strand and reduced to the yarn size desired thru successive operations and without imparting any permanent twist thereto.

By providing a false twist in the yarn between the upper and lower nips, the edges are turned inwardly and a more even draft is provided and the fray with consequent loss of fibers is reduced to a minimum and by this false twist the fibers 145 are maintained in their desired compact relation and sufficient strength is given to the thread as it passes thru the different operations. Also by revolving the rotary members and the nip rolls in opposite direction a lower speed may be used 150

for the revolving of the rolls in order that a false twist may be provided.

The foregoing description is directed solely towards the construction illustrated, but I desire it to be understood that I reserve the privilege of resorting to all the mechanical changes to which the device is susceptible, the invention being defined and limited only by the terms of the appended claims.

10 I claim:

1. In a long draft spinning apparatus, a plurality of pairs of nip rolls, means for separately rotating the rolls of each pair about its own axis, means for revolving one of the pairs of rolls about an axis passing between the rolls and at an angle to the axis of the rolls, and means for traversing one of the rolls of each pair with reference to its other roll.

2. In a long draft spinning apparatus, a plurality of pairs of nip rolls, means for revolving the pairs of rolls about an axis passing between the rolls at an angle to the axis of the rolls, means for rotating said rolls, each about its own axis, and means for traversing one of the rolls of each pair with reference to the other roll.

3. In a long draft spinning apparatus, a plurality of pairs of nip rolls, means for revolving the pairs of rolls of adjacent pairs in opposite directions about an axis passing between the rolls at an angle to the axis of the rolls, means for rotating the rolls of each pair about its own axis, and means for traversing one of the rolls of each pair with reference to its other roll.

4. In a spinning apparatus, a plurality of superimposed decks, driving means adjacent to each deck, a removable operable unit slidably supported by each of said decks comprising a pair of nip rolls, and means connected with said driving means for rotating said nip rolls.

40 5. In a spinning apparatus, a plurality of superimposed decks, driving means, a removable operable unit slidably supported by said decks comprising a pair of nip rolls, and means connected with said driving means for revolving said nip rolls about an axis passing between the rolls and at an angle to the axis of said rolls, and means rotating said nip rolls about their own axes.

50 6. In a spinning apparatus, a plurality of superimposed decks, driving means, a removable operable unit supported by said decks comprising a pair of nip rolls, means connected with said driving means for revolving said nip rolls about an axis passing between the rolls and at an angle to the axis of said rolls, means rotating said nip rolls about their own axes, and means for traversing one of the nip rolls of the pair with reference to the other roll.

60 7. In a spinning apparatus, a plurality of superimposed decks, driving means, a removable operable unit supported by said decks comprising a pair of nip rolls, means connected with said driving means for revolving said nip rolls about an axis passing between the rolls and at an angle

to the axis of said rolls, means rotating said nip rolls about their own axes, and means for traversing one of the nip rolls of the pair with reference to the other roll, said means being driven from said other roll.

8. In a spinning apparatus, a frame comprising a deck, driving means supported by said frame including a gear, a removable plate slidably supported by said deck, a member rotatably supported by said plate and provided with teeth to mesh with said gear and be driven thereby, nip rolls supported by said member, and means for rotating said nip rolls.

9. In a spinning apparatus, a frame comprising a deck, driving means supported by said frame including a gear, a plate slidably supported by said deck, a member rotatably supported by said plate and provided with teeth to mesh with said gear and be driven thereby, nip rolls supported by said member, means for rotating said nip rolls, and means for traversing one nip roll with respect to the other.

10. In a spinning apparatus, a frame comprising a plurality of superimposed decks, driving means supported by said frame and including a gear for each deck, a draft unit slidably supported by each deck and including a plate having a slidable engagement with the deck and provided with an opening with teeth about the edge thereof, a member rotatably supported by said plate and provided with teeth to mesh with one of said gears and be driven thereby, a spur gear supported by said rotary member and engaging the teeth in the edge of said opening to travel about with said member and be rotated by such movement, nip rolls on said member, means for driving said rolls from said spur gear.

11. In a spinning apparatus, a frame comprising a plurality of superimposed decks, driving means supported by said frame and including a gear for each deck, a draft unit slidably supported by each deck and including a plate having slidable engagement with the deck and provided with an opening with teeth about the edge thereof, a member rotatably supported by said plate and provided with teeth to mesh with one of said gears and be driven thereby, a spur gear supported by said rotary member and engaging the teeth in the edge of said opening to travel about with said member and be rotated by such movement, nip rolls on said member, means for driving said rolls from said spur gear, and gear cam lever and link means operated from one roll for causing the other roll to move axially with respect thereto.

12. In a long draft spinning apparatus, a plurality of pairs of nip rolls, means for separately rotating the rolls each pair about its own axis, means for revolving one of the pairs of rolls about an axis passing between the rolls and at an angle to the axis of the rolls, and means for traversing one of the rolls of said revolving pair of rolls with reference to its other roll.
